TRAIN-CONTROLLING MECHANISM.

1,108,584.

Specification of Letters Patent. Patented Aug. 25, 1914.

Application filed January 12, 1912. Serial No. 670,791.

To all whom it may concern:

Be it known that I, FRANK T. JONES, a citizen of the United States, residing at Baltimore, in the State of Maryland, have 5 invented certain new and useful Improvements in Train-Controlling Mechanism, of which the following is a specification.

This invention relates to improvements in train-controlling mechanism for railways 10 and has reference to an arrangement of electric circuits and devices whereby to materially simplify and improve mechanisms of this character.

Among other objects, the present invention aims to provide an improved arrangement of electric circuit on a vehicle including a contact shoe whereby a sudden actuation of the shoe brought about by the same striking something along the roadway that 15 is foreign to the train-controlling system will not result in an unnecessary automatic stop or automatic signal unless the contact shoe be so damaged as the result of such accidental contact as to render the system inoperative. These accidental contacts may 20 occur in many ways, as for example, by reason of the shoe striking a pile of dirt or stones along the roadway or by striking a loose plank at a road crossing or a bank of 25 snow piled too closely to the track rails.

Another result accomplished by the improvements herein is, the avoidance of an automatic stop when a train is traveling at a very much reduced speed, or a speed at 30 which it has been determined from experience which is safe regardless of the presence of a train or vehicle ahead. The speed here referred to being somewhere in the neighborhood of about five or six miles per hour, 35 but may be more or less.

The present invention preferably includes an automatically-actuated stop mechanism and an automatic signal mechanism to give a caution signal. Both of these elements are 40 carried on the vehicle, and are so arranged as to be controlled through contact shoes also carried by the vehicle which shoes are actuated by contact or ramp rails along the 45 roadway.

50 The particular constructions of the stop mechanism, signal mechanism and the contact shoes, is immaterial to the present invention, and I have found in actual practice that these elements may be of various constructions.

In connection with the improved vehicle or cab circuits and mechanisms, I have found it desirable to make use of a ramp rail which will impart to the contact shoes, when traveling over the same in one direction, a 60 more or less gradual instead of a sudden movement. The speed at which the vehicle is traveling will of course influence to some degree the speed at which the shoes operate when traveling over a ramp rail, but, at a 65 maximum speed of the vehicle, the upward movement of the shoes as they pass over the ramp rails will be sufficiently slow to effect such changes in the circuits as will produce the result desired,—that is give a signal or 70 stop if a block ahead is occupied or prevent such signal or stop if the block is clear. On the other hand, if the vehicle is traveling at the predetermined low speed the upward movement of the shoes while traveling over 75 the ramp rails will be too slow to give a stop whether a block ahead is occupied or not, but will give a caution signal.

It will therefore be understood that one of the features of the present invention is to 80 provide an arrangement of circuits and mechanisms whereby to retard the movement of the shoes in the direction imparted to them by reason of their contact with the ramp rails so as to enable the shifting of the 85 circuits to perform the functions demanded by the condition of the road ahead, and further to allow the said shoes to be actuated suddenly by accident without affecting either the signal or stop mechanism.

In case of a sudden shifting of the shoes by accidental contact with something outside of the system, the changing of the circuits will be so sudden as to prevent the 90 operation of either of the stop or caution signal mechanisms.

By means of the present invention the movement of a vehicle or train in a double track system against the direction of traffic may be permitted without giving either a 100 signal or stop because of the sudden operation of the contact shoes.

In carrying out the invention I have elected to show the invention in a diagrammatic manner in the accompanying drawings, wherein—

Figure 1, shows a portion of a roadway including the two rails which are so insulated as to produce independent blocks and also shows the stop and caution ramp 110

rails at the sides of the track rails and the current supply for each. Fig. 2 shows a ramp rail, merely illustrative of a form however which answers the requirements, and Fig. 3, illustrates in a diagrammatic way, the circuits and devices carried on the vehicle including the stop and signal devices and also the two contact shoes which operate in connection with those circuits.

As illustrative of the invention, I have shown in Fig. 1, a diagrammatic view of a portion of a trackway, wherein the numerals, 1, and, 2, designate the two rails of the track which rails are provided at intervals with suitable insulations, 3, whereby to form successive blocks, 4, 5, and, 6. Each block is provided near one end with a source of current supply, shown in the conventional way at, 7, 8, and, 9, respectively, and rail, 1, is connected to one side or pole of the current supply while rail, 2, is connected to the other side thereof. In the present illustration, each block is provided with two ramp rails,—one of which is designated, 10, and will be termed a signal ramp rail while the other is designated, 11, and will be referred to as the stop ramp rail. In the present instance the signal ramp rails, 10, are located at the outer side of the track rail, 1, while the stop ramp rail is shown at the outer side of the track rail, 2. This arrangement of the ramp rails is not at all necessary however, as obviously they may be located between the rails or both at the same side of a track rail.

The preferred form of ramp rail, whether it be the signal or stop ramp rail, is indicated in Fig. 2, merely to show that I prefer a rail having a long gradually-inclined upper contact surface, 12, and a sharp, steep or abrupt inclined surface, 13, at the end. This abrupt inclined surface is provided at the rear end of the ramp rail where the contact shoes carried on the vehicle will pass from the rail as will hereinafter be more fully set forth. Obviously no attempt is made in the drawings to show the precise construction of the ramp rails or the manner of securing them in place, and the drawing is merely illustrative of a long gradual incline and a short abrupt incline which are utilized to advantage in the practical operation of my invention, as has been demonstrated in actual railroad practice.

By again referring to Fig. 1, it will be seen that only those track circuits are illustrated which connect the caution signal, ramp rail and the stop ramp rail which guard block, 6,—the said caution ramp rail for which is located in the present instance adjacent to block, 4, and the said stop ramp rail being located in block, 5. At the entrance end to block, 6, the track-rail, 1, is provided with a wire connection, 14, which electrically connects said rail with an elec-

tro-magnet, 15, while another wire, 16, extends from said magnet to and connects with rail, 2. An armature, 17, is located adjacent to the core of magnet, 15, whereby it may be attracted and held in a given position, as long as said magnet is energized. The energization of this magnet, 15, is effected by a current from the local supply, 9, of block, 6,—the circuit being from one pole of said supply, 9, through one of the track rails, say rail, 1, to wire, 14, then through magnet 15, and return by wire, 16, and rail, 2, back to said supply, 9. This circuit through magnet, 15, is maintained as long as the current can flow through the rails, 1, and, 2, to and from wires, 14, and, 16, respectively, which is obviously as long as there is nothing to bridge across said rails between said supply, 9, and the points where wires, 14, and, 16, connect with said rails, 85 such for example as during the presence of a vehicle or a train.

The armature, 17, serves as a switch to maintain a current in line wires, 18, and, 19, respectively from a battery, 20, or other current supply, as long as the magnet, 15, is energized. These line wires, 18, and, 19, extend back along the blocks, 5, and, 4, and connect with electro-magnets, 21, and, 22,—the magnet 21, being connected to the line wires, 18, and, 19, through suitable branch wires, 23, and, 24.

From the foregoing explanation it will be seen that as long as magnet, 15, is energized, which is so long as block, 6, is clear, the armature, 17, will close the circuit between battery, 20, and line wires, 18, and, 19, and thus complete a circuit from the said battery through both electro-magnets, 21, and, 22, and keep said latter magnets 105 energized.

By again referring to Fig. 1, it will be noted that electro-magnet, 21, as long as it is energized, attracts an armature, 25, and that a wire, 26, connects said armature with the stop ramp rail, 11. Another wire, 27, has one end attached to track rail, 2, and its other end connected to one pole of a battery, 28, or other current supply. From the other pole of said battery, 28, a wire, 29, extends 115 to a point where it will be brought into contact with armature, 25, during such time as the latter is held in the attracted position by magnet, 21.

From the foregoing explanation it will be understood that stop ramp rail, 11, during all periods of safety conditions in block, 6, is connected with one side of battery, 28, while track rail, 2, at the same time is connected to the other side of said battery,—the only break from one pole of the battery to the other pole being the lack of a connection between track rail, 2, and stop ramp rail, 11. This connection is supplied through the vehicle as will presently be explained. 130

Passing rearwardly now to the caution ramp rail at block, 4, it will be noted that an armature, 30, is provided at electro-magnet, 22, which armature is also held in an attracted position by said magnet as long as block, 6, is clear. This armature, 30, has a connection with signal ramp rail, 10, by wire, 31, and another connection, as long as the armature is attracted, with one pole of a battery or other current supply, 32, by means of a wire, 33. A wire, 34, connects the other side or pole of battery, 32, with either track rail, 1, or, 2, as desired,—in the present instance the connection being with rail, 1. In the case of this signal ramp rail, 10, it will thus be seen that during all periods of safety or clear conditions in block, 6, said ramp rail, 10, is connected with one pole of battery, 32, while track rail, 1, at the same time is connected to the other side or pole of said battery, 32,—the only break in this case being the lack of connection between the ramp rail, 10, and the track rail, 1, which is supplied by the vehicle while passing the said rail, 10.

In the practical operation of the invention the locomotive, motor or other vehicle, is provided with two contact shoes,—one being termed the signal contact or shoe and the other the stop contact or shoe,—it being understood by the terms selected that the signal shoe is that one which will contact with and travel over the signal ramp rails while the stop shoe is that one which contacts with and travels over the stop ramp rails. If these two sets of ramp rails are located on opposite sides of the track, then one contact will be located on one side of the vehicle while the other will be located on the opposite side of said vehicle.

By reference to Fig. 3, of the drawings, the circuits and devices carried on the vehicle will be explained. As ramp rails for two different purposes are employed along the roadway, the vehicle will be provided with two separate and independent contact shoes. In the diagrammatic illustration, it does not appear just what positions these shoes have on the vehicle, but it will be understood that the positions will of course be such as to enable each shoe to be brought into successive contact with only those contact rails which have to do with the mechanism they are intended to operate. In said Fig. 3, the caution signal contact shoe, 35, which will hereinafter be referred to as the signal shoe, is so mounted that its forward end, 36, will ride up the long gradual incline surface of the signal ramp rails as it passes over the latter, and by this means said forward end at least will gradually raise or move upwardly, but will drop again after passing onto the steep incline surface at the rear end of the said ramp rail. This signal contact shoe, 35, included in a normal

signal circuit on the vehicle while the latter is traveling between adjacent signal ramp rails and said circuit embraces wire, 37, electro-magnet, 38, wires, 39, 40, and, 41, which latter connects with one pole of a battery, 42, or other source of electric energy. From the other pole of said battery, 42, the normal signal circuit returns by wire, 43, to an armature, 44, which is controlled by magnet, 38, and from said armature by wires to a contact plate, 46, switch, 47, and wire, 48, back to the shoe, 35. It will thus be seen that the normal signal circuit from battery, 42, to shoe, 36, and return, includes electro-magnet, 38, which it energizes, and by the energization of which, the armature, 44, is held in the attracted position. In connection with this armature, 44, there is shown in a diagrammatic way, a signal arm, 49,—a link, 50, connecting the arm with the armature so as to elevate the arm when the armature is held up and to lower the said arm when armature, 44, drops upon the deenergization of magnet, 38.

It will be noted that the signal shoe, 35, is diagrammatically shown as being mechanically connected with the switch, 47, through a rod or bar, 51, so that when said shoe is elevated by the inclined surface of a signal ramp rail, 10, during the passage of the shoe over said rail, the upward movement of the shoe will cause the rod or bar, 51, to be raised and thus move the switch, 47, from contact plate, 46. When this connection between switch, 47, and contact, 46, is broken it is obvious that the circuit on the vehicle from battery, 42, through signal magnet, 38, will be interrupted or broken and give a caution signal unless a current from some source other than from battery, 42, is substituted. If the current from battery, 42, is cut-off from magnet, 38, of course the deenergization of that magnet will follow, and the armature, 44, will drop and move the signal arm, 49, on the vehicle to a caution position, thus giving notice to the operator to proceed with caution because of a train or vehicle in block, 6, ahead. If on the other hand, there is no train in block, 6, the electro track magnet, 15, (see Fig. 1) will be kept energized; armature, 17, will close the circuit from battery, 20, through line wires, 18, and, 19; electro-magnet, 22, will be kept energized and armature, 30, will maintain a connection from one pole of battery, 32, to the signal ramp rail, 10, by wire, 31, while the other pole of battery, 32, is connected to a track rail, in this case rail, 1, of section or block, 4.

From the foregoing explanation it will be seen that when signal shoe, 35, rides up the inclined surface, 12, of the signal ramp rail, 10, and conditions of safety prevail in block, 6, the upward movement of the shoe, 35,

will interrupt the normal signal circuit on the vehicle from battery, 42, through magnet, 38, and switch, 47, but another circuit will be completed from signal rail, 10, and battery, 32, and will be substituted before the switch, 47, breaks from contact, 46, which is of such form or shape as to allow a slight movement of the switch before the break takes place. This substitute circuit 10 will be formed as follows: From one pole of battery, 32, by wire, 33, armature, 30, and wire, 31, to signal rail, 10; then by signal shoe, 35, which at that time is on signal rail 10, by wire, 37, to electro-magnet, 38, to 15 energize the latter; then by wires, 39, 40, and, 41, to a wire, 52, which connects with the axle, 53, so that the wheel, 54, by contact with track rail, 1, will complete the circuit through wire, 34, back to the other pole 20 of battery, 32. By means of this substitute circuit it will thus be seen that during periods of safety conditions ahead, the travel of the signal shoe over signal rail, 10, will form a substitute circuit which will maintain the signal on the vehicle at the safety 25 position and that as the shoe leaves said rail, 10, the lowering of the latter will re-establish the normal circuit from battery, 42, and thereby maintain the signal circuit 30 while the vehicle is traveling from one signal rail to another. This operation of the signal circuit takes place regardless of the speed of the vehicle, provided of course, that block, 6, is clear. If block, 6, is occupied 35 by another train or vehicle the presence of the latter will produce a short circuit from battery 9, through the wheels and axle to rails, 1, and, 2, and consequently current from said block battery, 9, cannot pass back through electro-magnet, 15, and the latter would become deenergized; break the circuit from battery, 20, through, line wires, 18, and, 19; thus deenergizing electro-magnet, 22, and by allowing armature, 30, drop 40 break the connection between battery, 32, and the track and ramp rail, 1, and, 10, so that the shoe cannot pick up the circuit from battery, 32, to substitute it for the normal signal circuit on the vehicle and consequently 45 magnet, 38, on the vehicle would be deenergized and signal arm, 49, would drop to caution by the falling of armature, 44.

In connection with the signal shoe, 35, I provide means whereby the accidental contact of the same with something foreign to or not a part of the system will prevent the giving of a caution signal, but as this mechanism coacts with and performs a like function with respect to the stop shoe, these devices will be described after the stop mechanism and circuits have been explained.

By referring to Fig. 3, it will be noted that an electro-magnet, 55, is located in a case, 56, the latter being situated on the vehicle in any suitable place. This magnet

controls armature, 57, which is suitably attached to valve mechanism (not shown) in the air-brake system so that during energization of the said magnet the valve mechanism will be held in a position to allow the usual operations of the brakes but when the magnet is deenergized a venting of the train line will follow because of the movement of the armature, 57, and thus cause an application of the brakes.

A step shoe, 58, is carried on the vehicle in such position that it will ride over the stop ramp rails, 11, as the vehicle passes the latter. The particular construction of this stop shoe, 58, is not essential to the present invention, but it is preferably so mounted that during its passage over the stop rail, 11, it will be gradually raised because of the inclined upper surface of the said rail and by the upward motion so change or entirely interrupt circuits as to cause a stop (by the application of the brakes) or not according to the conditions of the track ahead. In the present form to the stop shoe is attached one end of a rod, 59, which latter is diagrammatically illustrated as being connected to two switch bars, 60, and, 61, respectively. The switch bar, 60, normally engages a contact plate, 62, while the bar, 61, normally contacts with another plate, 63, but may be moved by the movement of the stop shoe, 58, and rod, 59, so as to be brought into contact with another plate, 64.

The circuit by which the electro-magnet, 55, is normally kept energized is from one pole of battery, 42, on the vehicle by wires, 41, 40, and 65, to said magnet; then by wire, 66, to stop shoe, 58, by wire, 67, to switch-bar, 60, and contact plate, 62; then by wires, 68, and, 43, back to the other pole of battery, 42. It will thus be seen that electro-magnet, 55, is normally energized by a current that passes from battery, 42, through the magnet, the shoe, 58, and switch bar, 61, and then back to the battery. This condition prevails while the stop shoe is traveling from the stop rail, 11, of one block to the stop rail of the next block.

When the stop shoe reaches a stop rail and begins its travel up the upper inclined surface of the latter, the condition of the track ahead will determine what will take place on the vehicle. If the track ahead is occupied and the vehicle is traveling above, say five or six miles per hour, then as the shoe comes in contact with stop rail, 11, and is elevated, both switch-bars, 60, and, 61, will be moved from engagement with contact plates, 62, and, 63, and the normal stop circuit on the vehicle from battery, 42, will be broken, thus deenergizing electro-magnet, 55, and effecting an application of the brakes to stop the train. On the other hand, if the track ahead is not occupied, but is in good condi-

tion and clear, a current will be picked up by the stop shoe, 58, from rail, 11,—the current being supplied by a local battery, 28, and said current will pass by way of the 5 shoe, 58, wire, 66, to magnet, 55, then by wires, 65, 40, 41, and, 52, to axle, 53, wheel, 54, and track rail, 2, and finally from track rail, 2, by wire, 27, back to battery, 28, thus completing the circuit and substituting a local 10 current on the vehicle during the period that the normal current on the vehicle is broken by the stop rail, 11, raising the shoe, 58.

In practice, I have discovered that it is 15 desirable to provide for two conditions that might exist both of which would cause an application of the brakes when it is preferably desired that no such application be made. One of these conditions is that when 20 a train is proceeding slowly and below a predetermined rate of speed, (say five or six miles per hour) it shall be permitted to approach a train ahead of it and even enter the block wherein the other train or vehicle 25 is located without first having the brakes automatically applied. The circuits and mechanism employed to accomplish this will now be described.

It will be recalled that both the caution 30 ramp rail, 10, and the stop ramp rail, 11, have been described as having a long gradually-inclined upper surface, 12, which will effect a gradual raising of the shoes passing over them. This gradual elevation of the 35 shoes is obviously slower when the vehicle is moving at a very low rate of speed than at a higher speed, and as this present example has to do with the very slow speed, (below six miles per hour) the subject will be 40 discussed from that point of view first.

It will be noted in Fig. 3, that a relay magnet, 69, is provided as a part of the vehicle equipment and that said magnet controls an armature, 70, which is connected by 45 wires or conductors, 71, and, 72, with another wire, 67, that is attached to the stop shoe, 58. A plate, 73, serves as a contact for armature, 70, when the latter is held in the attracted position by the magnet, 69, and a 50 conductor, 74, connects said plate, 73, with the conductor or wire, 68, that leads to one pole of battery, 42, by wire, 43. To normally energize the relay magnet, 69, I provide a circuit from the vehicle battery, 42, 55 which circuit from one pole of the battery, includes the wire, 41, wire, 75, that extends to the relay magnet, 69, wire, 76, from the said magnet to a contact plate, 77, and switch-bar, 78, adjacent to the rod that is 60 actuated by the signal shoes, and wire, 79, that connects the switch-bar, 78, with contact plate, 63, from which the relay circuit will normally be completed by switch-bar, 61, wire, 72, switch-bar, 60, to contact plate, 62, and finally by wires, 68, and, 43, back to 65 the other pole of the vehicle battery, 42.

By referring to Fig. 3, it will be seen that a contact plate, 80, is provided adjacent to the movable end of switch-bar, 78, so that when the latter is moved by the rod, 51, 70 and caution signal shoe, 35, said switch-bar, 78, will pass from contact plate, 77, onto contact plate, 80. Now suppose the vehicle to be traveling at a very low speed, because of a caution signal previously given, 75 when the stop shoe, 58, rides up on the long gradually-inclined surface of stop ramp rail, 11, the fact that the vehicle is proceeding slowly together with the fact that the incline of the stop rail is gradual, will cause 80 the stop shoe, 58, to move upwardly very slowly and in doing so the rod, 59, will lift switch bars, 60, and, 61,—the former holding on to its contact with plate, 62, until the switch-bar, 61, makes contact with plate, 85 64. As soon as bar, 61, breaks connection from contact plate, 63, relay magnet, 69, will become deenergized and armature, 70, will drop for a moment that is, only during the time consumed by the switch bar, 61, 90 traveling from contact, 63, to contact, 64. As soon as switch bar, 61, makes contact with plate, 64, which is before switch, 60, has left plate, 62, a circuit to again energize relay magnet, 69, will be formed from 95 vehicle battery, 42, by wires, 41, and, 75, to said relay, then by wires, 76, and, 81, to contact, 64, with which bar, 61, at that moment contacts; then by said switch bar, 61, to wire, 72, and through switch bar, 60, 100 which has not yet broken from contact plate, 62, and through the latter to wire, 68, back to battery, 42, by wire, 43. This momentary circuit will again energize relay magnet, 69, and return armature, 70, to contact with 105 point, 73, so that, before bar, 60, leaves contact, 62, the stop circuit through stop magnet, 55, will continue through switch, 60, to wire, 68, until this connection is broken and will then be by wire, 72, and, 71, and armature, 70, and wire, 74, to wire, 68, so that at no moment will the circuit through stop magnet, 55, be interrupted while the vehicle is traveling below the predetermined slow speed of five or six miles per hour, no 110 matter what conditions prevail in the block ahead. The return movement of the stop shoe will effect a reverse switching of the circuits to keep the stop magnet energized. On the other hand in case the vehicle or 115 train is traveling at a speed in excess of the predetermined low speed of say five or six miles per hour, the switch bar, 60, will move much faster because the stop shoe will pass up the incline surface of the stop ramp rail 120 more quickly, and the movement of said bar, 60, from contact, 62, will be much quicker and so shorten the interval between the break 125

of bar, 61, from, 63, and the contact of said bar, 61, with plate, 64, that the relay magnet, 69, which was deenergized when the switch, 61, left contact, 63, will not have time to become again energized and attract armature, 70, before bar, 60, leaves contact, 62, consequently armature, 70, will remain in the released position and the current from stop magnet, 55, through wire or connection, 10 67, cannot pass through switch bar, 60, because of the break from contact plate, 62, and cannot pass through connection, 71, and armature, 70, because the latter is out of contact with point, 73, and the stop circuit 15 will thus be broken and stop magnet, 55, deenergized which will result in applying the brakes. It is thus to be understood that when traveling under five or six miles (more or less) per hour the stop circuit through 20 magnet, 55, will not be interrupted, even if the block ahead is occupied, whereas at a speed above that last named with same condition in block ahead the stop circuit will be interrupted and a stop will follow. Now 25 suppose the vehicle or train to be traveling and some obstruction along the roadway other than the ramp rail should contact with the stop shoe, 58, and throw it up, unless some means be provided to prevent it, the 30 stop magnet, 55, would be deenergized and the brakes applied, which would be objectionable. I have provided means to overcome this which will now be explained.

Most any obstruction that would accidentally move the contact shoe would cause the latter to move very rapidly and much more rapidly than it would do by contact with a ramp rail whose upper surface is specially inclined to gradually raise the shoe 40 even when the vehicle is moving rapidly. A sudden operation of the shoe such as would necessarily result in the present example, would cause the switch bars, 60, and, 61, to be shifted very rapidly so that bar, 61, 45 would contact with plate, 64, very rapidly and before the armature, 70, would fall. This shifting of bar, 61, would form a circuit through said relay magnet as follows: From battery, 42, by wire, 43, to wires, 68, 50 and, 74, to contact point, 73; then through armature 70, to wire, 71, and switch bar, 61, to contact, 64, and then by wires, 81, and, 76, through relay-magnet, 69, and finally from said magnet by wires, 75, and, 41, back 55 to battery, 42. By means of this latter circuit the relay magnet would not become deenergized and would hold armature, 70, in contact with point, 73, so that the stop circuit through magnet, 55, would be maintained from battery, 42, by wires, 43, 68, and, 74, to contact, 73, then through armature, 70, and wires, 71, 72, and, 67, to stop shoe, 58, then by wire, 66, to stop magnet, 55, and from the latter by wires, 65, 40, and, 41, 60 back to vehicle battery, 42.

It is to be understood that at all times when caution is proper a caution signal will be given, whether the vehicle is traveling slowly or fast, because it is desired that the operator be informed of the condition ahead 70 so he can slow down when it is proper to do so, but in case the caution shoe, 35, should be accidentally operated by contact with some object outside of the system, then and only then will the shoe be actuated without 75 giving a caution signal. This operation is very much the same as has been described in connection with the stop shoe, the circuits however are different and will therefore be explained. The rapid movement of the caution shoe, 35, as the result of sudden contact with some outside object will cause a sudden movement to caution switch bar, 47, from contact plate, 46, and a like movement of bar, 78, from contact, 77, to contact, 80. 80 These movements of bars, 47, and, 78, from contacts, 46, and, 77, respectively would be practically simultaneous and too fast for the relay magnet, 69, to become deenergized while the switch-bars, 47, and, 78, are in motion. The circuit which then holds the relay magnet, 69, will be from battery, 42, by wires, 43, and, 68, to plate, 62; through switch bar, 60, and wire, 72, to switch bar, 61; then by contact, 63, to wire, 79, and to switch bar, 78, which is then in engagement with contact, 80; then by wire, 76, to relay magnet, 69, and from the latter by wires, 75, and, 41, back to battery, 42. During this sudden change of the circuits to prevent deenergization of electro-magnet, 69, the maintenance of that magnet will enable a signal circuit to be maintained that will prevent the operation of signal magnet, 38. 100 This latter circuit is as follows:—From battery, 42, by wires, 41, 40, and, 39, to signal magnet, 38; then by wire, 37, shoe, 35, and wire, 48, to wire, 82, then through armature, 83, that is held attracted to contact point, 84, and wire, 85, to wire, 45; then through armature, 44, and wire, 43, back to battery, 42. By this means relay-magnet, 69, will control two armatures, 70, and, 83, which will serve to keep stop and signal magnets, 55, and, 38, energized while the contact shoes are making quick movements in case of their operations by accidental contact with some object outside of the system. 110 115

Another desirable feature resulting from the arrangement of circuits and mechanism hereinbefore described is that when a vehicle or train is moving over a track against the direction of traffic neither the stop or signal mechanism will be actuated on the vehicle because the sharp inclined end, 13, of the ramp rails will impart a sudden motion to the stop and signal shoes which will effect a change in the circuits precisely the same as though said shoes had suddenly come in contact with an object outside of the system. 120 125 130

Of course, in moving against traffic the track circuits would be so changed as to warn vehicles or trains approaching the backing vehicle or train but no stop signal will be actuated on the backing vehicle.

5 It is to be understood that the expression wires throughout the specification is used in a general way and is to be interpreted as including any form of conductor that will 10 serve the function of a wire.

Having thus described my invention what I claim and desire to secure by Letters Patent is,—

1. In a train-controlling mechanism for 15 railways having track rails which are insulated at intervals to form blocks or sections, and also having ramp rails adjacent to the track rails, in combination with a vehicle having a controlling device with a 20 magnet to control the same; a contact shoe on the vehicle to engage and be moved by the ramp rails; a circuit on the vehicle including the magnet and shoe when the vehicle is traveling between ramp rails; a relay 25 also on the vehicle; a normal circuit to energize the relay and means operated by the shoe to close a substitute circuit through the relay and maintain a circuit through the controlling device magnet at times when the 30 normal circuit through said magnet is interrupted by a movement of the shoe.

2. A train-controlling mechanism for railways having track rails which are insulated at intervals to form blocks or sections and 35 also having ramp rails adjacent to the track rails, in combination with a vehicle having a safety device thereon, of an electro-magnet to control said safety device and hold the same normally inoperative; a contact shoe 40 also on the vehicle to coat with and be moved by the ramp rails along the trackway; a circuit on the vehicle normally including a current supply on the vehicle and also including the said electro-magnet and 45 contact shoe while the shoe is in its normal inoperative position so as to keep said magnet energized, and means actuated by the shoe for electrically maintaining said safety device in the said normal inoperative position upon a sudden movement of the shoe.

3. A train-controlling mechanism for railways having track rails which are insulated at intervals to form blocks or sections and also having ramp rails adjacent to the track 55 rails, in combination with a vehicle having a normally inoperative safety device thereon; an electro-magnet to control said safety device; a contact shoe also on the vehicle to coat with and be moved by the ramp rails 60 along the trackway; a normal circuit on the vehicle including a current supply on the vehicle and also including the said electro-magnet and contact shoe while the shoe is in its normal inoperative position to keep 65 the said magnet energized; a relay magnet;

a circuit on the vehicle which normally energizes said relay-magnet, and means operated by the shoe for electrically forming another circuit through the relay to enable the latter to maintain a circuit through the 70 electro-magnet that controls the said safety device.

4. A train-controlling mechanism for railways having track rails insulated from each other to form blocks or sections, in combination with a vehicle having a normally inoperative safety device thereon; an electro-magnet for controlling said safety device; a contact shoe also on the vehicle; a normal circuit on the vehicle including a current supply on the vehicle and also including said electro-magnet and contact shoe while the shoe is in its normal inoperative position to keep the magnet energized; ramp rails at 80 intervals along the track to coat with and cause a movement of the contact shoe on the vehicle,—said ramp rails having an inclined contact surface whereby to move said shoe fast or slow according to the speed of the vehicle, and means controlled by a slow 85 movement of the shoe for electrically maintaining the said electro-magnet in an energized condition.

5. A train-controlling mechanism for railways which latter have track rails insulated from each other to form blocks or sections and also having ramp rails adjacent to the track rails; in combination with a vehicle having a normally inoperative safety device thereon, of an electro-magnet for controlling said safety device; a contact shoe on the vehicle; a switch on the vehicle; means connecting the switch and shoe; a normal circuit on the vehicle including a current supply on the vehicle and also including the 95 electro-magnet, switch and shoe while the latter is in the normal inoperative position to maintain the safety device in said inoperative position; a relay magnet; an armature for said relay magnet, and a circuit including the said electro-magnet, shoe and armature to maintain the safety device in the 100 inoperative position.

6. A train-controlling mechanism for railways which latter have track rails insulated from each other to form blocks or sections and also having ramp rails adjacent to the track rails, in combination with a vehicle having a normally inoperative safety device, of an electro-magnet for controlling said 115 safety device; a contact shoe on the vehicle; a switch also on the vehicle and having a plurality of movable contact plates; and a greater number of stationary contacts,—said contacts being so arranged that one movable 120 plate will move from one stationary contact to another before another movable contact has left its stationary contact; mechanical means connecting the shoe and the movable contact plates to cause the plates to move 125 130

when the shoe is moved; a circuit on the vehicle including a current supply, the electro-magnet, shoe, and one movable contact plate to keep the said electro-magnet energized while the shoe is in the normal inoperative position; a relay magnet having an armature; a circuit normally including at least one of said movable contact plates and said relay magnet to hold the armature in the attracted position, and means actuated by the shoe for forming another circuit including the relay magnet, the shoe and the armature of the relay magnet to maintain the safety device in the inoperated position at times while the shoe is in the operated position.

7. A train-controlling mechanism for railways that have track rails insulated from each other to form blocks or sections and also having stop ramp rails at intervals along the tracks, in combination with a vehicle having an air-brake valve; an electro-magnet to hold the air-brake valve normally in an inoperative position; a stop contact shoe to engage and be operated by the successive stop ramp rails; a circuit on the vehicle which normally includes a current supply, said electro-magnet and contact shoe to hold the air-brake valve in the inoperative position while the shoe is in its normal inoperated position and be interrupted by the shoe engaging a ramp rail; and means controlled by the stop contact shoe when the latter is moved by a ramp rail to prevent the actuation of the air-brake valve when the vehicle is traveling below a predetermined rate of speed.

8. A train-controlling mechanism for railways that have track rails insulated from each other to form blocks or sections and also having stop ramp rails at intervals along the tracks, in combination with a vehicle having an air-brake valve; an electro-magnet to hold the air-brake valve normally in an inoperative position; a stop contact shoe to engage and be operated by the stop ramp rails; a circuit on the vehicle which normally includes a current supply, said electro-magnet and contact shoe to keep the valve in the inoperative position while the shoe is also in the inoperative position; a switch; a relay having an armature; a circuit including the relay, switch and current supply to keep the relay normally energized and hold its armature attracted, mechanical means connecting the shoe and switch for operating the switch when the shoe is operated by a ramp rail to interrupt the normal circuit through the valve magnet and a substitute circuit formed by the switch through the said relay to maintain a circuit through said valve magnet upon a sudden and accidental movement of the stop shoe.

9. A train-controlling mechanism for railways that have track rails insulated from

each other to form blocks or sections and also having stop ramp rails at intervals along the tracks, in combination with a vehicle having an air-brake valve; an electro-magnet for normally holding said valve in an inoperative position; a stop contact shoe to engage and be moved by the stop ramp rails; a plurality of switches; contacts for the switches; a source of current on the vehicle; a circuit on the vehicle normally including the source of current, the electro-magnet which controls the air-brake valve, stop contact shoe and one of said switches and its contacts said normal circuit being interrupted by the shoe engaging a stop ramp rail; a relay; a circuit normally including the relay and another of said switches and contacts while the stop shoe is in the said inoperative position; mechanical means operated by the stop shoe to actuate the switches upon a movement of the shoe to interrupt the normal circuits through the electro-magnet and the relay and a substitute circuit formed through the relay from the source of supply on the vehicle to maintain a circuit through the valve magnet.

10. A train controlling mechanism for railways that have track rails insulated from each other to form blocks or sections and which also have stop ramp rails at intervals along the tracks, in combination with a vehicle having an air-brake valve; an electro-magnet for normally holding said valve in an inoperative position; a stop contact shoe to engage and be moved by the stop ramp rails; a plurality of switches; contacts for the switches; a source of current on the vehicle; a circuit on the vehicle normally including the said source of current, the electro-magnet, contact shoe and one of said switches and contacts to keep the air-brake valve in the inoperative position while the shoe is in the inoperative position; a relay magnet; an armature coacting with said relay-magnet; a circuit including the relay magnet and another of said switches and contacts to normally energize said relay magnet; a shunt connection from the stop contact shoe around the switches and including the armature of said relay magnet to provide a substitute circuit through the electro-magnet, shoe and armature at times while the shoe is in the operated position and mechanical means connecting the stop shoe and said switches to shift the latter and close a circuit through the relay magnet when the shoe is moved suddenly.

11. A train - controlling mechanism for railways that have track rails insulated from each other to form blocks and also having ramp rails at intervals along the tracks, in combination with a vehicle having a normal inoperative caution signal device, a signal magnet to normally hold the caution signal in the inoperative position; 130

an air-brake valve; a valve magnet to normally hold the air-brake valve in the inoperative position; a signal contact shoe; a stop contact shoe; a circuit normally including the signal magnet and signal contact shoe while the signal shoe is in the inoperative position; a circuit normally including the air-brake valve magnet and the stop contact shoe while the stop shoe is in the inoperative position, and electrical means controlled by said shoes to provide a substitute circuit through the signal and valve magnets during the sudden operation of the signal or stop shoe.

12. A train-controlling mechanism for railways that have track rails insulated from each other to form blocks and which also have signal and stop ramp rails at intervals along the tracks in combination with a vehicle having a caution signal device; a signal magnet to normally hold the caution signal in the safety position; an air-brake valve; a valve magnet to normally hold the air-brake valve in the inoperative position; a signal contact shoe to engage and be moved by the signal ramp rails; a stop contact shoe to engage and be

moved by the stop ramp rails; a circuit on the vehicle normally including the signal magnet and the signal contact shoe to energize the signal magnet; a circuit also on the vehicle normally including the valve magnet and the stop contact shoe to energize the valve magnet; switches interposed in said normal signal and stop circuits; mechanical connections between the signal shoe and its switches and between the stop shoe and its switches; a relay; a circuit normally including the relay, one of the signal and one of the stop switches; a plurality of stop switch contacts and a plurality of signal switch contacts said switches being so arranged with respect to their contacts that a slow movement of the shoes will close circuits through the switches and their contacts to 45 actuate the signal device in case of danger and maintain the valve magnet in an energized condition.

In testimony whereof I affix my signature in presence of two witnesses.

FRANK T. JONES.
